CLAIM

The ornamental design for a computer host, as shown and described.

DESCRIPTION

FIG. 1 is a perspective view of a computer host showing a first embodiment of our new design;
 FIG. 2 is a front view of the first embodiment;
 FIG. 3 is a rear view of the first embodiment;
 FIG. 4 is a left side view of the first embodiment;
 FIG. 5 is a right side view of the first embodiment;
 FIG. 6 is a top view of the first embodiment;
 FIG. 7 is a bottom view of the first embodiment;
 FIG. 8 is an enlarged view of the portion, labeled '8' of FIG. 1;
 FIG. 9 is an enlarged view of the portion, labeled '9' of FIG. 4;
 FIG. 10 is a perspective view of the first embodiment with the hanging portion opened;
 FIG. 11 is another perspective view of the first embodiment with the hanging portion opened;
 FIG. 12 is an enlarged view of the portion, labeled '12' of FIG. 10;
 FIG. 13 is an enlarged view of the portion, labeled '13' of FIG. 11;
 FIG. 14 is a perspective view of a computer host showing a second embodiment of our new design;
 FIG. 15 is a front view of the second embodiment;
 FIG. 16 is a rear view of the second embodiment;
 FIG. 17 is a left side view of the second embodiment;
 FIG. 18 is a right side view of the second embodiment;

FIG. 19 is a top view of the second embodiment;
 FIG. 20 is a bottom view of the second embodiment;
 FIG. 21 is an enlarged view of the portion, labeled '21' of FIG. 14;
 FIG. 22 is an enlarged view of the portion, labeled '22' of FIG. 18;
 FIG. 23 is a perspective view of the second embodiment with the hanging portion opened;
 FIG. 24 is another perspective view of the second embodiment with the hanging portion opened;
 FIG. 25 is an enlarged view of the portion, labeled '25' of FIG. 23;
 FIG. 26 is an enlarged view of the portion, labeled '26' of FIG. 24;
 FIG. 27 is a perspective view of a computer host showing a third embodiment of our new design;
 FIG. 28 is another perspective view of the third embodiment;
 FIG. 29 is a front view of the third embodiment;
 FIG. 30 is a rear view of the third embodiment;
 FIG. 31 is a left side view of the third embodiment;
 FIG. 32 is a right side view of the third embodiment;
 FIG. 33 is a top view of the third embodiment;
 FIG. 34 is a bottom view of the third embodiment;
 FIG. 35 is an enlarged view of the portion, labeled '35' of FIG. 27;
 FIG. 36 is an enlarged view of the portion, labeled '36' of FIG. 28;
 FIG. 37 is an enlarged view of the portion, labeled '37' of FIG. 31;
 FIG. 38 is an enlarged view of the portion, labeled '38' of FIG. 32;
 FIG. 39 is a front, left, top perspective view of the third embodiment with the hanging portion at the left side opened;
 FIG. 40 is a front, left, bottom perspective view of the third embodiment with the hanging portion at the left side opened;
 FIG. 41 is an enlarged view of the portion, labeled '41' of FIG. 39;
 FIG. 42 is an enlarged view of the portion, labeled '42' of FIG. 40;
 FIG. 43 is a front, right, top perspective view of the third embodiment with the hanging portion at the right side opened;
 FIG. 44 is a front, right, bottom perspective view of the third embodiment with the hanging portion at the right side opened;
 FIG. 45 is an enlarged view of the portion, labeled '45' of FIG. 43;
 FIG. 46 is an enlarged view of the portion, labeled '46' of FIG. 44; and,
 FIG. 47 is a front view of the third embodiment with the hanging portions opened.
 The dashed broken lines illustrate portions of the computer host and form no part of the claimed design. The dot-dash broken lines showing the boundaries of the claimed design form no part thereof. The dot-dash broken lines indicating and labeling enlarged views form no part of the claimed design.
